Thurston & Bates.

UNITED STATES PATENT OFFICE.

GEORGE C. WORTHINGTON, OF ELYRIA, OHIO.

COMBINED KNIFE AND FORK SUPPORT AND KNIFE-SHARPENER.

SPECIFICATION forming part of Letters Patent No. 712,228, dated October 28, 1902.

Application filed December 23, 1901. Serial No. 86,903. (No model.)

To all whom it may concern:

Be it known that I, GEORGE C. WORTHINGTON, a citizen of the United States, residing at Elyria, in the county of Lorain and State 5 of Ohio, have invented a certain new and useful Improvement in a Combined Knife and Fork Support and Knife-Sharpener, of which the following is a full, clear, and exact description, reference being had to the accompanying drawings.

The object of the invention is to provide a new article of manufacture sufficiently neat in appearance to be unobjectionable on a well-set dining-table, adapted to support the soiled 15 blade of the carving-knife and the tang of the fork, and to afford means for sharpening said knife.

The invention consists of a plate having at its ends downwardly-projecting legs where- 20 with it is supported, combined with a knife- sharpener lying above the said plate and secured thereto about midway between the ends thereof.

It also consists in the more specific char- 25 acteristics of the device, as shown in the drawings, and hereinafter described, and pointed out definitely in the claims.

In the drawings, Figure 1 is a perspective 30 view of my invention; Fig. 2 is a plan view, and Fig. 3 a side elevation thereof.

I will now describe the embodiment of the invention shown in the drawings, which is the best form thereof now known to me.

Referring to the parts by letters, A represents a plate, preferably made of sheet metal. 35 Projecting upward from its side edges about midway between its ends are the integral ears $a^1 a^2$. Each end of the plate is slotted longitudinally to form three tongues $a^3 a^4 a^5$, of 40 which the two outside tongues are bent downward to form legs upon which the article stands, and the intermediate tongue at each end is turned upward to form a guard which will prevent a knife and fork resting upon 45 the plate, as shown in the dotted lines of Fig. 1, from slipping off of the ends thereof.

A knife-sharpener B is secured to the plate A about midway between its ends, said sharpener consisting of two screw-threaded rods $b^1 b^2$, fitted between the ears $a^1 a^2$, secured thereto 50 with their screw-threads intermeshing substantially as shown. The edge of the knife to be sharpened is put into the crease between these intermeshing screws and drawn along lengthwise, the result being that the sharp 55 edges of the screw-threads will shave or scrape the metal from the knife-blade, and thereby put a good carving edge thereupon.

Having described my invention, I claim—

1. In a combined knife and fork support 60 and knife-sharpener, the combination of a plate longitudinally slotted at each end to form three tongues of which the outside tongues are turned down to form legs and the intermediate tongues are turned up to form guards, 65 ears extending upward on the sides thereof, and intermeshing circumferentially-grooved rods mounted between said ears, substantially as specified.

2. As a new article of manufacture, a com- 70 bined knife and fork support and knife-sharpener consisting of a plate having downwardly-extending legs at its ends, ears extending upward on the side thereof, and two intermeshing circumferentially-grooved rods lying be- 75 tween and secured to said ears, substantially as specified.

3. As a new article of manufacture, a com- 80 bined knife and fork support and knife-sharpener consisting of a plate having downwardly-extending legs at its ends, ears extending upward on the side thereof, and two intermeshing screw-threaded rods lying between and secured to said ears, substantially as specified.

In testimony whereof I hereunto affix my 85 signature in the presence of two witnesses.

GEORGE C. WORTHINGTON.

Witnesses:
